UNITED STATES PATENT OFFICE.

FRED F. BILLINGS, OF BELMONT, NEW HAMPSHIRE.

SINKER FOR KNITTING MACHINES.

Application filed May 24, 1926. Serial No. 111,366.

This invention relates to cylinder knitting machines and more particularly to hand operated cylinder machines, in which it is desirable to have free access to all parts of 5 the cylinder and dial for the purpose of transferring stitches and removing needles in the process of knitting.

The primary object of this invention is to provide a novel sinker mounted directly on 10 the cylinder wall without the use of an extraneous frame, ring or other supporting means with the exception of a retaining spring.

Another object of the invention is the 15 provision of a set of sinkers of original form equal in number to the needles with which they are used with novel means for mounting the sinkers on the wall of a knitting machine cylinder in proper relation to 20 the needles and a cam for automatically operating the sinkers in proper timed relation.

The advantages of sinkers in knitting machine construction to facilitate speed and accuracy of performance are well known, 25 but heretofore it has been deemed impossible to use them on machines of the type mentioned above because, in common practice, the ring or frame required for mounting such sinkers formed an obstruction 30 which cut off ready access to the work in process of completion within the machine.

It is therefore another salient object of the invention to eliminate the difficulty mentioned above by making available, a simple, 35 free running and inexpensive sinker mechanism, requiring no other frame than the wall of the cylinder itself.

A still further object of the invention is to provide a novel sinker construction and 40 operating means of the character described, which will be durable and efficient in use, one that will be simple and easy to manufacture and one which can be placed upon the market and incorporated with a cylinder knitting machine at a small cost.

With these and other objects in view, the invention consists in the novel construction, arrangement and formation of parts, as will be hereinafter more specifically described, 45 claimed, and illustrated in the accompanying drawings, in which drawings:

Figure 1 is a top plan view of a portion of a hand operated cylinder knitting machine showing the set of sinkers incorporated therewith and the cams for operating the same,

Figure 2 is a side elevation of a portion of a hand operated cylinder knitting machine showing the sets of novel sinkers incorporated therewith and the cam for actuating the same,

Figure 3 is an enlarged detail section through the wall of the cylinder of the knitting machine showing the novel means employed for mounting one of the novel sinkers in place, the view showing the normal position of the sinker,

Figure 4 is a view similar to Figure 3 showing the sinker in its operated position.

Referring to the drawings in detail, 70 wherein similar reference characters designate corresponding parts throughout the several views, the letter A generally indicates a cylinder knitting machine comprising a cylinder 5 having a plurality of vertical slots 6 for the reception of the usual needles 7. The wall of the cylinder 5 intermediate the slots 6 is provided with vertically disposed radial grooves 8 for the reception of the novel sinkers 9, which are of a special 80 construction, and which will be hereinafter specifically described. It is to be noted at the present time that each groove 8 gradually decreases in depth toward its lower end and that the inner wall of the groove at a 85 point intermediate the ends of the groove is provided with a relatively deep arcuate recess 10 for receiving a portion of the sinker 9 which will be also described.

Rotatably mounted on the cylinder 5 is 90 the cam shell 11 which is actuated in the usual manner and carries the ordinary V-stitch cam 12 and the cam shell 11 is operated in either direction as common to all knitting machines. At one side of the V- 95 stitch cam 12, the cam shell 11 has secured thereto the usual yarn guide support, which in the present instance has secured to its inner face, a bumper 14, which forms a part of the present invention.

Each sinker 9 comprises a single piece of 100 formed metal having a body portion 15 by which it is maintained in proper alignment, and an inwardly and downwardly directed arm 16 is formed on the inner edge of the body 15 adjacent to the upper end thereof and this arm projects through a slot in the upper edge of the cylinder and terminates in a hook 17, the purpose of which will be 105 described. The body portion 15 at its inner edge is provided with an inwardly directed bearing portion 18 which is fitted 110

within the recess 10, by which it is kept at a fixed height with respect to the top of the cylinder and in which it is free to exercise a slight oscillating motion as will be described. Directly below the bearing portion 18 the body is provided with an outwardly directed butt portion or trip arm 19 through which the motion is communicated to the sinker as a whole. The upper portion of the body 15 terminates in a work hook 20 of a form and function common to all sinkers. The function of this hook is to seize the edge of the knitted web between the stitches as each course of stitches is formed by the needles, to "sink" it to its proper level and to hold it there until the stitch in the next course higher up is about to be formed, when it must open outwardly for a brief interval to allow the reception of the yarn for the new stitch. The arm 16 of the sinker 9 is of such form as to extend through to the interior of the needle cylinder 5 where its hooked extremity 17 receives an annular helical retaining spring 21, which passes around the inside of the cylinder and likewise engages every sinker in the set. The inward pull of the spring 21 acting on all of the sinkers together is sufficient to hold them in place on the cylinder, so that they function freely without any other means of support. The retaining spring 22 on the exterior of the cylinder is for retaining the needles only and the notch 23 in the outer face of the body 15 of each sinker is to permit the passage of the spring around the same.

It is necessary, however, that a part of the body 15 of the sinker be imbedded in the cylinder wall under the needle retaining spring 22 and for this reason the notch 23 is cut from the body of the sinker and the bearing portion 18 of the form of the arc of a circle is made concentric with the center of the said notch 23, so that the sinker is able to oscillate about the spring 22 as a center, but on a bearing entirely separate therefrom, thus avoiding interference with the needle retaining spring 22. The bearing for the sinker is completed by having a part of its groove in the cylinder cut in a corresponding arcuate form, concentric with the needle retaining spring groove 23, but of slightly less arc than the bearing portion of the sinker. In this groove or notch 10 the sinker rests and oscillates.

Motion is imparted to the sinkers by a cam 25 pivotally mounted on a post 26 at the center of the V-stitch cam 12. This cam 25 has two working faces 27 and 28, which are pressed alternately against the sinker butts or trips 19, which project into its path. This pressure causes an oscillation of the sinkers and consequently an outward motion of the hooks at their upper extremities. This motion passes in a wave

along the line of sinkers as the cam shell 11 with its attended cams progresses in its revolution around the cylinder 5. It is necessary that this open space in the series of sinkers 9 be maintained slightly in advance of the center of the stitch cam 12, as this is the point at which the yarn is drawn into the web by the needles 7. To accomplish this, the ends of the cam 25 are disposed in the path of the yarn guide supporting arm 13, which is so made as to assume a fixed position in advance of the stitch cam 12, no matter in which direction the machine is being run.

The cam trip or bumper 14 is suitably located on the yarn guide supporting arm 13 for bringing the ends of the cam 25 toward the cylinder, thereby bringing the working face of the cam into action on the sinkers 9 which lie on the leading side of the stitch cam 12. When the machine is reversed, the action is automatically transferred to the opposite end of the cam 25. The arm 16 of each sinker 9 terminates in a depending portion 16' which acts as a guard to prevent the newly started web from becoming entangled with the hooks 17.

From the foregoing description, it can be seen that novel means has been provided for mounting sinkers on a cylinder knitting machine directly on the cylinder without the use of extraneous supporting means, and which are so constructed and arranged as to perform their function properly without interference with any other parts of the machine.

Changes in details may be made without departing from the spirit or scope of this invention, but:

What I claim as new is:

1. In a cylinder knitting machine, a cylinder having slots formed therein, a set of sinkers having body portions directly mounted on the wall of the cylinder and having arms thereon extending interiorly of the cylinder in spaced relation to the body portions, and a single spring engaging the inner faces of all of said arms.

2. In a cylinder knitting machine, a cylinder having slots formed therein, sinkers 115 rockably mounted on the outer face of the wall of the cylinder, inwardly and downwardly directed arms on the sinkers extending through the slots terminating in hooks and a spring engaging the hooks for holding the sinkers in place.

3. In a cylinder knitting machine, a cylinder having a plurality of slots therein, a set of sinkers having bearings formed thereon, the wall of the cylinder below the slots 125 in alignment therewith having bearing grooves for receiving the bearings of the sinkers, arms formed on the sinkers extending through the slots and directed downwardly toward the interior of the cylinder,

and an annular spring engaging the arms for holding the sinkers in position.

4. In a cylinder knitting machine, a cylinder having slots formed therein, a sinker mounted exteriorly of the cylinder for rocking movement thereon having an arm projecting through the slots to the interior of the cylinder, and a single spring engaging the arms for holding the sinkers in place without the use of any extraneous supports.
5. In a cylinder knitting machine, a cylinder having a plurality of slots therein, needles mounted in the slots, the cylinder having slots between the needle slots, a sinker in alignment with each of the last mentioned slots, an arm on the sinker extending through the last mentioned slots into the interior of the cylinder, an annular spring engaging the arms for holding the same in position, an exterior spring surrounding the cylinder for holding the needles, each sinker having an arcuate recess for receiving the last mentioned spring and a bearing on each sinker engaging the wall of the cylinder concentric with but separate from the last mentioned spring, as and for the purpose specified.

6. In a cylinder knitting machine, a cylinder having slots therein, needles positioned in the slots, means for holding the needles in place, the cylinder also having sinker slots formed therein intermediate the needle slots, a sinker for each slot, an arm on each sinker projecting through the slots to the interior of the cylinder, resilient means engaging the arms for holding the sinker in position, trip arms formed on the ends of the sinkers, a cam shell rotatable about the cylinder, a

stitch cam on the cylinder, a cam pivotally mounted on the center line of the stitch cam 40 for engaging the trip arms for actuating said sinkers.

7. In a cylinder knitting machine, a cylinder having needle slots therein and sinker slots intermediate the needle slots, a cam 45 shell revoluble about the cylinder, a sinker for each sinker slot, an arm on each sinker projecting through the sinker slot to the interior of the cylinder, a radially extending trip arm on the lower end of each sinker, a 50 sinker operating cam on the cam shell having working faces on its opposite end to engage alternately with the trip arms, and a yarn engaging arm on the cam shell for engaging either end of said sinker operating 55 cam according to the direction of rotation of said shell.

8. A sinker comprising a body, an arm on the body, a spring holding hook on the arm, and a guard extending beyond the hook to 60 prevent the knitted web from being tangled in said hook.

9. A sinker comprising a body, an arcuate arm formed on the inner edge of the body adjacent to the upper end thereof, a yarn engaging hook on the body above the arm, a holding hook on the arm, a guard for said hook on the arm below the hook, an angularly extending trip arm on the lower end 70 of the body projecting in a direction opposite to the first mentioned arm, an arcuate notch in the body above the trip arm, and a bearing portion on the inner edge of the body concentric with said notch.

In testimony whereof I affix my signature.
FRED F. BILLINGS.
